UNITED STATES PATENT OFFICE.

GEORGE A. BELL AND WILLIAM W. NORMAN, OF MORLEY, MISSOURI.

EXTENSION STEP-LADDER.

SPECIFICATION forming part of Letters Patent No. 287,793, dated November 6, 1883.

Application filed August 22, 1883. (No model.)

To all whom it may concern:

Be it known that we, GEORGE A. BELL and WILLIAM W. NORMAN, citizens of the United States, residing at Morley, in the county of Scott, State of Missouri, have invented an Extension Step-Ladder, of which the following is a specification.

Our invention relates to grooved extensible ladders having slotted stiles and supports or legs, the same being in sections, and held together by bolts working in the slots of the stiles and supports, said ladder being provided with hinged brace-rods having pins in the outer ends working in the slots of the stiles and supports, and the spring-catches, whereby to regulate the adjustment of the sections. This ladder can be raised or lowered to suit all elevations; can be taken apart and used single; can be drawn out either from the top or from the bottom. We attain these objects by the mechanism illustrated in the accompanying drawings, in which—

Figure 1 represents the ladder with the extension down, and shows the hinged brace-rods in position. Fig. 2 shows the ladder folded, also the brace-rods. Fig. 3 shows the ladder extended to its full height.

Letter A represents the hinged brace-rods, fastened at the outer ends by the bolts B B, working in the slots.

C C are the spring-catches, which are in-

serted near the top of the stiles and supports, and the points of said catches go through the outside stiles and supports and enter thimbled holes D D, which are in the inside stiles 35 and supports.

E E are the slots.

G and H are cross brace-bars on the legs or supports.

Fig. 4 shows the hinged brace-rods. Fig. 5 40 is the catch, with the spring F, which works the catch. Fig. 6 shows the hinging of the top of the ladder. Fig. 7 is a section on line a a of Fig. 2, showing the arrangement and operation of the catch in the stiles.

We are aware that prior to our invention there have been grooved extensible step-ladders. We therefore do not wish to make our claims too broad; but

What we do claim, and desire to secure Letters Patent for, is—

The combination of the front and rear slotted portions, the hinged brace-rods having pins in the outer ends working in the slots of the stiles and legs or supports, and the spring-catches, 55 whereby to regulate the adjustment of the sections, all substantially as specified.

GEORGE ALBERT BELL.
WILLIAM W. NORMAN.
